US00D733774S

(12) United States Design Patent
Moon et al.

(10) Patent No.: US D733,774 S
(45) Date of Patent:  Jul. 7, 2015

(54) HOME APPLIANCE

(71) Applicant: Samsung Electronics Co., Ltd., Suwon-si (KR)

(72) Inventors: Ji-Hyun Moon, Gwangmyeong-Si (KR); Sang-Min Hyun, Seoul (KR); Jong-Chan Kwon, Yongin-Si (KR); Jin-Il Ryu, Seoul (KR); Yang-Jic Lee, Gwachon-Si (KR)

(73) Assignee: Samsung Electronics Co., Ltd., Suwon-si (KR)

() Term: 14 Years

(21) Appl. No.: 29/466,465

(22) Filed: Sep. 9, 2013

(30) Foreign Application Priority Data

Mar. 8, 2013 (KR) 30-2013-0011838

(51) LOC (10) Cl. 15-07

(52) U.S. Cl.

USPC D15/91

(57) CLAIM

The ornamental design for a home appliance, as shown and described.

DESCRIPTION

FIG. 1 is a front perspective view of a home appliance showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof; shown in an open position.

The broken lines shown in FIG. 6 and FIG. 8 of the drawings show unclaimed subject matter only and form no part of the claimed design. The shade lines in the figures show contour and not surface ornamentation.
